ROUNDING MACHINE

Lloyd G. Miller, Beverly, Mass., assignor to United
Shoe Machinery Corporation, Borough of Flem-
ington, N. J., a corporation of New Jersey

Application June 1, 1939, Serial No. 276,846

13 Claims. (Cl. 12—25)

This invention relates to machines by which work-pieces, such as shoe-soles, are formed to a desired peripheral contour by a traveling knife guided by a pattern, the work-pieces being located with relation to the pattern by gaging means.

An organization of the character of that indicated above is disclosed in Letters Patent of the United States No. 2,139,485, Bertrand, December 6, 1938. In this apparatus, the gaging means is normally in active co-operation with the pattern and is moved away when the work is clamped for the operation upon it, so contact with it of the traveling knife mechanism is avoided. If the gaging means is not thus withdrawn from the pattern and maintained in an inactive relation, it will be struck by the knife mechanism and the machine injured. It is an object of my invention to guard against such an accident in a simple and effective manner and without interfering with the usual elements of the machine.

To attain this end, I add to the previously mentioned pattern, knife and gage, together with means, as lever mechanism, movable to control the travel of the knife, means movable with the gage into position to be engaged by an element moving with the controlling means to govern the movement thereof, as by preventing its movement until the gage is withdrawn from the path of the knife. This safety means may be applied with little change in the customary machine-structure and may be so located that such parts as those of a motor-drive may remain undisturbed. Moreover, after the gage has been removed from the path of the knife, I provide means for preventing it from again assuming its active position while the knife is in motion. The means for preventing movement of the knife-controlling means and the return of the gage to its active position is herein shown as furnished by a single member, which may be movable with the gage. The particular form of the invention disclosed herein utilizes lever mechanism for controlling the travel of the knife and treadle mechanism through which the gage is moved, there being members movable with these respective mechanisms which co-operate to guard against mistimed movement, either of the lever mechanism, the treadle mechanism or both. More specifically, a block carried upon a cable which joins the treadle mechanism to the gage, and a projection from the lever mechanism for controlling the knife, co-operate in the control both of the lever mechanism and the treadle mechanism and therefore the position of the gage.

The accompanying drawing shows a single possible embodiment of my invention.

Fig. 1 illustrating in side elevation portions of a sole-rounding machine with the associated novel elements, all being in their normal positions; while

Fig. 2 is a detail in side elevation upon a smaller scale than Fig. 1, and in which the starting lever appears as actuated.

The machine, in connection with which I have chosen to disclose my invention, is of the well known Planet type, it being provided with the work-gaging means of the patent previously referred to. A pattern 10 is fixed in position upon the frame 12 of the machine and the work, as a sole-blank, is secured in place upon it by a clamp 14, carried by a spindle 16 arranged to reciprocate vertically in an overhanging frame-arm 18. The clamp is caused to descend to engage the work by connections (not illustrated) to treadle mechanism T, mounted at the bottom of the frame. Supported upon a block 20 is a knife 22 actuated to travel under the guidance of the pattern, about its periphery, to form a clamped blank. As is fully set forth in Letters Patent of the United States No. 1,048,511, Eaton, December 31, 1912, when a lever 24, fulcrumed at 26 upon the frame, is depressed, the engagement of an unillustrated clutch causes the travel of the knife about the pattern, the lever being held down during an operating cycle by a latch 28 (Fig. 2) and automatically released and restored to its normal position at the termination of the cycle. At this time, a lever 30, fulcrumed at 32 and linked to the lever 24 at 34, applies a brake to the driving element of the clutch to check the advance of the knife. To locate the blank before it is clamped, gaging mechanism is associated with the pattern. One or more gage members 38 are each mounted upon a carrier 40, secured to the lower extremity of an arm 42 fast upon such a shaft as 44, rotatable in an extension from the frame-arm 18. Attached to another arm 46 projecting upwardly from the shaft is a connecting member in the form of a cable 48, which is joined at 50 to a movable element of the treadle mechanism T. When the treadle is in its normal elevated position, these connections permit the gage mechanism to assume the position appearing in Fig. 1 of the drawing, in its active relation to the pattern, ready to determine the correct location of a blank. The gaging of the blank having been accomplished, the operator depresses the treadle to lower the clamp 14 and secure the work for the rounding operation. The action of the trea-

idle mechanism applies tension to the cable 48, rotating the shaft 44 to move the gage 38 outwardly and upwardly clear of the path of the knife mechanism. The operator then throws down the hand-lever 24 to the position illustrated in Fig. 2, where it is temporarily retained by the latch 28. The power mechanism is brought into action to cause the knife 22 to travel about the pattern and cut the clamped blank to the desired form. When the knife reaches its normal position, the lever 24 is freed and rises, disconnecting power from the knife and applying the brake to the driven member of the clutch through the lever 30. Upon release of the treadle, all the elements will have been restored to normal.

It will be seen that, with the rounding apparatus as above outlined, to avoid damage to its elements, the treadle mechanism and starting lever mechanism must be operated in a definite sequence. Were the starting lever to be actuated and the clutch engaged before depression of the treadle, the gage 38 would lie in the path of the knife mechanism and breakage would result. Further, were the treadle released during the travel of the knife, the same thing might occur. Both these conditions are rendered impossible by my invention. About the cable 48 is secured a tubular supporting member or sleeve, formed in two sections 52 and 54, which may be joined by a right-and-left threaded sleeve 56, so there is furnished means for taking up slack in the connections. Threaded for vertical adjustment upon the section 52, is a contact-block 58, which, to hold it against displacement, may be backed by an abutment 60 rising from a bracket 62 fastened to the frame. From the brake-lever 30 rises a projection 64, the upper end of which is adjacent to the block 58. As will be seen by reference to Fig. 1, the block is so placed upon the support 52 that, when the treadle mechanism and the starting lever mechanism are in their initial positions, the end of the projection lies close to the side of the block. If the operator attempts to actuate the lever before depressing the treadle, and therefore with the gage still in the path of the knife, the projection will strike the block. This, held against rearward movement by the abutment 60, will prevent engagement of the lever-controlled clutch, and the power-cycle of the machine cannot be started. When the treadle is lowered and the gage elevated clear of the knife, the cable carries the block down to the level shown in Fig. 2. Now, the lever-projection 64 may pass over the top of the block, the movement being sufficient for the lever to assume its position beneath the latch 28, at which the clutch is engaged so the knife may make its operating circuit about the pattern. The starting lever is thus held by the latch until the power-cycle of the machine is completed. In Fig. 2, it will be seen that the end of the projection overhangs the top of the block and is in close proximity to it. Therefore, if the operator inadvertently releases the treadle, the block and cable will be held from rising and the gage will be locked in its elevated position, clear of the knife. When the knife has returned to its normal position and the clutch is disengaged, the lever is unlatched automatically and the operator may free the treadle, so the gage is restored to its active relation adjacent to the pattern. This causes the block to assume its initial, lever-locking position.

It will be seen that the elements by which I attain my novel result are few in number, readily applied to the machine and are so located that

they produce no interference. The arrangement is especially desirable, in that if a motor-drive is to be provided, the portion of the frame upon which the parts would be mounted is left free.

Having described my invention, what I claim as new and desire to secure by Letters Patent of the United States is:

1. In a rounding machine, a pattern, a work-gage movable into and out of co-operation with the pattern, a rounding knife traveling about the pattern, means movable to control the travel of the knife, and means movable with the gage into position to be engaged by an element moving with the controlling means to govern the movement thereof.

2. In a rounding machine, a pattern, a rounding knife traveling about the pattern, a work-gage movable between active and inactive positions, and means movable independently of the work-gage for preventing said work-gage from assuming its active position when the rounding knife is in motion.

3. In a rounding machine, a pattern, a rounding knife traveling about the pattern, a member movable to control the travel of the knife, a work-gage movable between active and inactive positions, a member movable independently of the first member to effect the gage-movement, and means including an element movable with the controlling member for preventing the work-gage from assuming its active position under the influence of its moving member.

4. In a rounding machine, a pattern, a work-gage movable into and out of co-operation with the pattern, a rounding knife traveling about the pattern, means movable to control the travel of the knife, and a member movable to two positions respectively preventing movement of the gage and of the controlling means.

5. In a rounding machine, a pattern, a work-gage movable into and out of co-operation with the pattern, a rounding knife traveling about the pattern, means movable to control the travel of the knife, and a member movable with the gage to govern the movement of said gage and of the controlling means.

6. In a rounding machine, a pattern, a rounding knife traveling about the pattern, lever mechanism for controlling the travel of the knife, a gage movable toward and from the pattern, treadle mechanism through which the gage is moved, and members movable with the lever mechanism and treadle mechanism respectively into positions in which they contact to prevent movement of the lever mechanism.

7. In a rounding machine, a pattern, a rounding knife traveling about the pattern, lever mechanism for controlling the travel of the knife, a gage movable toward and from the pattern, treadle mechanism through which the gage is moved, and members movable with the lever mechanism and treadle mechanism respectively and co-operating to prevent movement of the treadle mechanism.

8. In a rounding machine, a pattern, a rounding knife traveling about the pattern, lever mechanism for controlling the travel of the knife, a gage movable toward and from the pattern, treadle mechanism through which the gage is moved, and members movable with the lever mechanism and treadle mechanism respectively and co-operating to prevent movement of the lever mechanism to a position for initiating the travel of the knife and of the treadle mechanism to a

position permitting movement of the gage toward the pattern.

9. In a rounding machine, a pattern, a rounding knife traveling about the pattern, lever mechanism for controlling the travel of the knife, a gage movable toward and from the pattern, and treadle mechanism through which the gage is moved, the two mechanisms having elements movable into positions in which they contact to prevent actuation of the lever mechanism.

10. In a rounding machine, a pattern, a rounding knife traveling about the pattern, lever mechanism for controlling the travel of the knife, a gage movable toward and from the pattern, and treadle mechanism through which the gage is moved, the two mechanisms having elements movable into positions in which they contact to prevent release of the treadle mechanism.

11. In a rounding machine, a pattern, a rounding knife traveling about the pattern, lever mechanism for controlling the travel of the knife and having a projection, a gage movable toward and from the pattern, treadle mechanism, a cable joining the treadle mechanism to the gage, and

a block carried by the cable, the block being positioned for engagement by the projection when the treadle mechanism is unactuated.

12. In a rounding machine, a pattern, a rounding knife traveling about the pattern, lever mechanism for controlling the travel of the knife and having a projection, a gage movable toward and from the pattern, treadle mechanism, a cable joining the treadle mechanism to the gage, a block carried by the cable and arranged for engagement by the projection, and a fixed abutment for preventing displacement of the block by the projection.

13. In a rounding machine, a pattern, a rounding knife traveling about the pattern, lever mechanism for controlling the travel of the knife and having a projection, a gage movable toward and from the pattern, treadle mechanism, a cable joining the treadle mechanism to the gage, and a block carried by the cable, the projection being positioned for engagement by the block when the lever mechanism is actuated.
